UNITED STATES PATENT OFFICE.

JOHN MOOTRY BROWN, OF HAMILTON, ONTARIO, CANADA.

MACHINE FOR FOLDING STOVEPIPE BLANKS.

Application filed October 6, 1926. Serial No. 139,899.

My invention relates to improvements in machines for folding stove pipe blanks and the object of the invention is to devise a machine which will operate automatically to 5 form, by a series of successive steps, a double fold and an offset in a sheet metal blank placed in the machine, without necessitating any adjustment or attention by the operator between the various steps in the operation of the machine.

Other objects of the invention will appear in the course of the following specification.

My invention consists in the construction 15 and arrangement of parts all as hereinafter more particularly described and illustrated in the accompanying drawings in which:

Fig. 1 is a diagrammatic top plan view 20 of a machine embodying my invention.

Fig. 2 is a front elevation thereof looking in the direction of the arrow 2 in Fig. 1.

Fig. 3 is a rear elevation thereof looking in the direction of the arrow 3 in Fig. 1.

Fig. 4 is an end elevation thereof looking 25 in the direction of the arrow 4 in Figs. 1, 2 and 3.

Fig. 5 is a detached fragmentary section, 30 to a slightly enlarged scale, taken on the line 5—5 of Fig. 1 looking in the direction of the arrows.

Fig. 6 is a detached fragmentary section taken on the line 6—6 of Figs. 2 and 3.

Figs. 7, 8, 9, 10 and 11 are fragmentary 35 sections taken substantially on the line 7—7 of Fig. 1 showing the relative positions of the various parts during the successive steps in the operation of the machine.

Fig. 12 is a transverse section of a portion 40 of a stove pipe showing the nature of the completed double fold and offset formed by my machine.

In the drawings, like characters of reference indicate corresponding parts in the various views.

In the form illustrated my machine comprises a main frame or table 8 upon which is supported a superstructure comprising the end frame portions 9 connected at the top by a longitudinal portion 10.

A main drive shaft 11 is supported upon the main frame 8 being journaled in bearings 12 and carries at one end a drive pulley 13 and at the other end a gear 14.

For convenience of description this side 55 of the machine shall be referred to as the

front while the opposite side shall be referred to as the rear of the machine.

Adjacent to the front of the machine a shaft 15 is supported by the end frame portions 9 in bearings 16. This shaft projects 60 somewhat at either end of the machine and carries at the left hand end a gear 17 and at the right hand end a large gear 18 which meshes with the gear 14.

Co-acting between the gear 18 and the shaft 15 is a standard trip clutch 19 whereby the gear may be operatively connected with the shaft.

This clutch is connected by a system, indicated collectively by the numeral 20, with 70 a foot pedal 21 carried by a shaft 22 in such a manner that when the gears 14 and 18 are rotating, depression of the foot pedal will trip the clutch 19 and operatively connect the gear 18 to the shaft 15 for one revolution at the end of which period the clutch will be automatically disconnected so that the gear 18 will rotate freely upon the shaft 15 until the pedal 21 is again depressed.

The full and exact detail of this clutch has 80 not been illustrated or described as it may be of any of the standard types well known and used in machine design and since I do not consider it to be novel in any way nor do I claim it as a part of my present invention further description thereof is not thought necessary and the illustration thereof is merely diagrammatic.

Journalled in the end frame portions 9 at the top thereof is a shaft 23 which projects somewhat beyond the left hand end of the frame and carries a gear 24.

Adjacent to the rear of the machine a shaft 25 is supported by the frame portions 9 in bearings 26. This shaft projects somewhat beyond the left end of the frame and carries a gear 27.

A central bearing 34 is provided for the shaft 25 and a central bearing 35 is provided for the shaft 23.

An idler gear 28 operatively connects the gears 17 and 24, said idler gear being fixed upon a stub shaft 29 which is journalled in bearings 30.

A second idler gear 31 operatively connects the gears 24 and 27, said idler gear being fixed upon a stub shaft 32 which is journalled in bearings 33.

It will thus be seen that the gears 17, 28, 110 24, 31 and 27 constitute an operatively con-

nected gear train so that the shafts 15, 23 and 25 rotate in unison.

Extending longitudinally of the machine and freely seated in a recess 36 in the upper face of the table 8 is a bar 37 fitted into one side of which is a face piece 38 which projects somewhat above the top of the bar.

The bar 37 is resiliently supported from below upon a number of longitudinally spaced apart coil springs 39 the lower ends of which are set in depressions 40 in the bottom of the recess 36 (see Figs. 4 and 5). These coil springs 39 operate to urge the bar upwardly and to cause it to normally project above the top of the table 8.

At longitudinally spaced apart points of the bar 37 are blocks 41 slidably in recesses 42 in the rear face of the bar which blocks are urged outwardly by coil springs 43 seated within the recesses 42, (see Fig. 5).

Extending longitudinally of the top face of the table 8 immediately in front of the piece 38 is a shallow depression or recess 44 which will be hereinafter referred to.

25 A substantially horizontally disposed ram 45 is supported above the table 8 in front of the bar 37 which ram is fitted with a face piece 46 formed with a V-shaped depression or recess 47.

30 This ram 45 is adapted for reciprocation forwardly and rearwardly and also for up and down movement as will presently be explained and is supported from below upon pins 48 at either end thereof which pins 35 are freely mounted in recesses 49 in the table 8, the pins being urged upwardly by coil springs 50 located within these recesses.

In this way the ram 45 is normally urged upwardly away from the table 8.

35 Fixedly carried by the ram 45 and extending forwardly therefrom are two arms 51 at the forward extremities of which are mounted rollers 52.

40 Fixedly mounted upon the shaft 15 are two cams 53 positioned to co-operate with the rollers 52.

45 At each end of the ram 45 is a coil spring 54 one end of which is connected to the ram, the other being connected to a bracket 55 fixedly carried by the frame.

50 These springs 54 therefore operate to pull the ram 45 forwardly towards the front of the machine and maintain the rollers 52 in contact with the cams 53 so that during the rotation of the shaft 15 and cams 53 the ram 45 is reciprocated back and forth as the contour of the cams passes over the rollers 52.

55 In the illustrations in Figs. 1 to 5 inclusive the ram 45 is shown in its innermost or rearmost position.

Opposed to the ram 45 and located on the opposite side of the bar 37 is a second substantially horizontal ram 56 supported above the table 8 and has fitted into its front

edge, extending the entire length of the ram, a projecting tongue 57.

This ram 56 is adapted for reciprocation forwardly and rearwardly and also for up and down movement as will presently be explained and in its rearmost position illustrated in Figs. 1 to 5 inclusive its forward edge slightly overlies the bar 37 so that this bar forms a support for the front end of this ram.

75 The tongue 57 is so positioned that it will just clear the top of the face piece 38 when the ram 56 moves forwardly.

Fixedly carried by the ram 56 and extending rearwardly therefrom are two arms 58 at the rear extremities of which are mounted rollers 59.

80 Fixedly mounted upon the shaft 25 are two cams 60 positioned to co-operate with the rollers 59.

85 Fixedly carried by the ram 56 and extending rearwardly therefrom are two arms 61 provided with cylindrical bearing orifices extending thereinto from the rear ends thereof and engaged within these orifices are plungers 62, the rear ends of which carry bearing blocks 63 in which the shaft 25 is journaled.

90 At the rear side of the ram 56 are two depending brackets 64 and mounted at the rear side of the table 8 are two upstanding brackets 65.

95 Two coil springs 66 have their opposite ends connected to the brackets 64 and 65 so that these springs operate to pull the ram 56 rearwardly towards the rear of the machine and to maintain the rollers 59 in contact with the cams 60.

100 During the rotation of the shaft 25 and cams 60 the ram 56 is reciprocated back and forth as the contour of the cams 60 passes over the rollers 59 and the plungers 62 move in and out within the bearing orifices in the arms 61.

105 It will be noted that due to the manner of supporting the rear end of the ram 56 by the plungers 62 a certain degree of freedom of up and down motion is permitted to the ram 56 the purpose of which will be presently explained.

110 Mounted upon the underside of the ram 56 are rods or bars 67 extending from rear to front of the ram, the rear end of these bars being upturned to overlie the rear face of the ram and set screws 68 are mounted in these upturned portions so as to engage the rear face of the ram and provide a means of adjusting the position of the bars 67 forwardly and rearwardly upon the ram.

115 The front ends of the bars 67 are offset at 69 to lie in spaced relation below the ram 56 and the forward ends of these offset portions abut the rear ends of the blocks 41 the purpose of which will presently be explained.

Supported directly above the shallow recess 44 in the table top is a vertical ram 70 extending longitudinally the full length of the rams 45 and 56 and immediately in front of this ram 70 and abutting thereagainst is another vertical ram 71 of the same length as ram 70.

The rams 70 and 71 lie alongside of each other and are supported in end guides 72. The lower end of the ram 71 abuts upon the top of the ram 45 and in the position illustrated in Figs. 4 and 5 in which the vertical rams 70 and 71 are in their topmost position the lower end of the ram 70 also abuts upon the top of the ram 45.

The abutting faces of the rams 70 and 71 lie vertically below the shaft 23 and vertical arms 73 and 74 are fixedly secured in recesses 75 and 76 (see Fig. 6) in the rams 70 and 71 respectively, which arms extend upwardly beyond the tops of these rams and carry at their upper ends rollers 77 and 78 respectively.

The rams 70 and 71 are also notched at 79 and 80 respectively, in their end faces, and the end frames 9 are each formed with a projection 81 (see Fig. 6) which engages within these notches and forms an additional guide for the rams in their up and down movement.

Fixedly carried by the shaft 23 are cams 82 and 83 so positioned as to engage the rollers 77 and 78 respectively.

Connecting the upper portion of ram 70 to the top frame member 10 are coil springs 84 (see Fig. 3) and similarly connecting the upper portion of ram 71 to the top frame member 10 are coil springs 85 (see Fig. 2) which springs operate to draw the rams upwardly and to maintain the rollers 77 and 78 in contact with the cams 82 and 83 respectively.

It will thus be evident that, during the rotation of the shaft 23 and with it the cams 82 and 83, the rams 70 and 71 will be reciprocated up and down.

Extending forwardly from the ram 71 are two arms 86 in each of which is slidably mounted a vertical pin 87 having an enlarged head which bears against the top of the arm. The lower end of each pin is secured to a holding down bar 88 and between this bar 88 and the bottom of the arm 86 are coil springs 89 urging this bar 88 downwardly.

The disposition of these parts is such that when the ram 71 is in its uppermost position (see Fig. 5), the bar 88 is raised to provide clearance between it and the table 8 to permit the insertion of the blank as will presently be explained.

At a number of longitudinally spaced apart points of the table are mounted arms 90 (see Fig. 5) the lower ends of which are pivotally connected to depending brackets 91 secured to the under side of the table 8.

These arms 90 project at an inclination upwardly through orifices 92 in the table and are normally resiliently maintained in their uppermost position by springs 93 encircling bolts 94, the upper ends of the bolts 94 being pivotally connected to the arms 90 and the lower ends extending through brackets 95 secured to the table. The lower ends of the bolts are threaded and carry nuts 96 to provide adjustment.

It will thus be seen that the upper ends of the arms 90 project at an inclination above the table top and act as guides to direct the sheet metal blank 97 upwardly as is desired in the operation of inserting it into position within the machine.

A stop or gauge 98 (see Fig. 1) is mounted upon the table at the front of the machine and is held in position by bolts 99, these bolts engaging slots 100 in the table, said slots being provided to enable the position of the stop 98 to be adjusted to suit requirements.

The operation of my machine is as follows:

A belt would be engaged upon the main drive pulley 13 so that whenever the machine is being operated the shaft 11 and gears 14 and 18 would be continuously rotated but the drive to the shaft 15 and gear train 17, 28, 24, 31, 27 would only be connected each time the foot pedal 21 was depressed and this connection would be maintained for one complete revolution of the gear 18 at the end of which the clutch 19 would automatically trip and disconnect this drive until the foot pedal 21 is again depressed.

The relation of the various parts is such that one complete revolution of the gear 18 operates the various parts of the machine through a complete cycle of steps to complete the formation of the double fold and offset in the blank after which it is removed and another blank inserted.

The various parts of the machine are initially in the positions illustrated in Figs. 1, 2, 3, 4, 5 and 7 and with the parts in these positions a sheet metal blank 97 is inserted from the front of the machine.

Since in this position the holding down bar 88 is raised above the table, the blank 97 may be freely passed thereunder.

In its passage inwardly or rearwardly the blank 97 is directed upwardly by the arms 90 so as to pass upwardly above the face piece 38 and tongue 57.

The blank 97 is properly positioned by engaging its front edge against the stop 98 which stop will have been adjusted for the particular size of blank being operated upon.

The position of the blank after insertion is as shown in Figs. 5 and 7.

The foot pedal 21 is now depressed to operatively connect the gear 18 to the shaft 15 and the following successive steps auto-

matically occur in forming the double fold and offset, which steps will be more clearly understood by reference in Figs. 7 to 11 inclusive.

5 In the first step the ram 71 descends forcing downwardly the ram 45 so that the face piece 46 bends the blank against the piece 38 into the form shown in Fig. 8. At the end of this step the relative positions of the 10 various parts are as shown in Fig. 8, the rams 56 and 70 having remained stationary.

In this step the bar 37 is prevented from descending by the engagement of the projecting blocks 41 upon the table 8.

15 Also in this operation as the ram 45 descends its supporting pins 48 are depressed into the recesses 49 in the table against the pressure of the springs 50.

When the ram 71 descends, the holding down bar 88 (see Fig. 5) engages the top face of the blank 97 and is held firmly thereagainst by the springs 89 so that the blank 97 is firmly held in position upon the table.

20 In the next step the ram 56 moves forwardly so that the tongue 57 thereof forces the blank into the V-shaped depression or recess 47 in the ram 45 bending the blank to conform to the shape of this depression. In this step the rams 45, 70 and 71 remain stationary and at the completion of the step the relative positions of the parts are as illustrated in Fig. 9.

Also in this step in its forward movement the ram 56 carries with it the bars 67 so that the offset forward ends 69 thereof depress the blocks 41 into the bar 37 against the pressure of the springs 43.

25 In the next step the ram 71 rises up a very slight amount just sufficient to relieve the pressure upon the ram 45 and this ram 45 withdraws forwardly to disengage the blank 97 from within the V-shaped depression 47. In this step the rams 56 and 70 remain stationary and at the completion of the step the relative positions of the parts are as illustrated in Fig. 10.

30 In the next step the ram 70 descends and completes the formation of the double fold and offset by flattening the bent portion of the blank and forcing it down into the shallow depression 44 in the table. In this operation the ram 56 remains in its forwardmost position but descends slightly being forced downwardly by the ram 70, which descent is permitted by the downward movement of the bar 37 against the pressure of the springs 39.

The bar 37 is now free to be forced downwardly since the blocks 41 are depressed thereinto and no longer project to engage the top of the table 8.

35 In this operation the tongue 57 remains within the fold of the blank so that this portion of the fold is not closed but is left open.

In the next and final step the ram 70 rises permitting the ram 56 and bar 37 to rise and the ram 56 withdraws rearwardly to its initial position permitting the blocks 41 to again project from the bar 37 and the cycle 70 of steps is completed with all parts returned to their initial relative positions shown in Figs. 5 and 7 after which the blank is removed and the machine is ready for the insertion of another blank. 75

The form of the completely formed blank is shown in Fig. 12.

It will thus be noted that the double fold and offset is formed in the blank in my machine by a series of successive automatic 80 steps requiring no attention by the operator beyond inserting the blank and setting the machine in operation by depressing the foot pedal.

From the foregoing it will be evident that I have devised a machine for folding stove pipe blanks whereby the objects of my invention have been attained. 85

Various modifications may be made in my invention without departing from the spirit thereof or the scope of the claims and therefore the exact forms shown are to be taken as illustrative only and not in a limiting sense and I desire that only such limitations shall be placed thereon as are imposed by the prior art or are specifically set forth in the appended claims. 95

What I claim as my invention is:

1. A machine for folding stove pipe blanks comprising a main table, a pair of opposed substantially horizontal rams supported above the table and movable both horizontally and vertically, one of said rams formed with a depression in its face and the other ram with a projecting tongue adapted to move into said depression, a vertical ram movable vertically above the table between the opposed rams, the table formed with a depression positioned vertically below the vertical ram and means for automatically operating said rams at predetermined intervals to constitute a complete cycle of forming operations. 105

2. A machine for folding stove pipe blanks comprising a main table 8, a pair of opposed substantially horizontal rams 45 and 56 supported above the table and movable both horizontally and vertically, the ram 45 formed with a depression 47 in its face and the ram 56 formed with a projecting tongue 57 adapted to move into the depression 47, a vertical ram 70 movable vertically above the table and between the opposed rams 45 and 56, the table formed with a depression 44 positioned vertically below the ram 70, a horizontally disposed bar 37 resiliently mounted in a recess 36 in the table and normally projecting above the table, said bar forming a support for the ram 56, means for locking said bar in 110 115 120 125 130

its uppermost position when the ram 56 is in one position, and means for permitting depression of said bar when the ram 56 is in another position, and means for automatically operating said rams at predetermined intervals to constitute a complete cycle of forming operations.

3. A machine for folding stove pipe blanks comprising a main table 8, a pair of opposed substantially horizontal rams 45 and 56 supported above the table and movable both horizontally and vertically, the ram 45 formed with a depression 47 in its face and the ram 56 formed with a projecting tongue 57 adapted to move into the depression 47, a vertical ram 70 movable vertically above the table and between the opposed rams 45 and 56, the table formed with a depression 44 positioned vertically below the ram 70, a horizontally disposed bar 37 resiliently mounted in a recess 36 in the table and normally projecting above the table, said bar forming a support for the ram 56, blocks 41 slidably mounted in recesses 42 in said bar 37, springs 43 mounted in the recesses 42 and normally urging said blocks outwardly to project beyond the bar 37, the under face of said projecting blocks resting upon the table to lock the bar in its uppermost position, and elements 69 carried by the ram 56 for depressing said blocks 41 into the bar to permit depression of the bar into the recess in the table, and means for automatically operating said rams at predetermined intervals to constitute a complete cycle of forming operations.

4. A machine for folding stove pipe blanks comprising a main table 8, a pair of opposed substantially horizontal rams 45 and 56 supported above the table and movable both horizontally and vertically, the ram 45 formed with a depression 47 in its face and the ram 56 formed with a projecting tongue 57 adapted to move into the depression 47, a vertical ram 70 movable vertically above the table and between the opposed

rams 45 and 56, a vertical ram 71 abutting the top of the ram 45 and adapted to depress said ram towards the table, the table formed with a depression 44 positioned vertically below the ram 70, a horizontally disposed bar 37 resiliently mounted in a recess 36 in the table and normally projecting above the table, said bar forming a support for the ram 56, means for locking said bar in its uppermost position when the ram 56 is in one position and means for permitting depression of said bar when the ram 56 is in another position, and means for automatically operating said rams at predetermined intervals to constitute a complete cycle of forming operations.

5. A machine for folding stove pipe blanks comprising a main table 8, a pair of opposed substantially horizontal rams 45 and 56 supported above the table and movable both horizontally and vertically, the ram 45 formed with a depression 47 in its face and the ram 56 formed with a projecting tongue 57 adapted to move into the depression 47, a vertical ram 70 movable vertically above the table and between the opposed rams 45 and 56, a vertical ram 71 abutting the top of the ram 45 and adapted to depress said ram towards the table, holding down means carried by the ram 71 and adapted to resiliently engage the table top when said ram is in its lowermost position, the table formed with a depression 44 positioned vertically below the ram 70, a horizontally disposed bar 37 resiliently mounted in a recess 36 in the table and normally projecting above the table, said bar forming a support for the ram 56, means for locking said bar in its uppermost position when the ram 56 is in one position and means for permitting depression of said bar when the ram 56 is in another position, and means for automatically operating said rams at predetermined intervals to constitute a complete cycle of forming operations.

JOHN MOOTRY BROWN.
